CLAIM

The ornamental design for a midsole and outsole for footwear, as shown and described.

DESCRIPTION

FIG. 1 is a perspective view of a midsole and outsole for footwear;

FIG. 2 is a right side view thereof;

FIG. 3 is a left side view thereof;

FIG. 4 is a top view thereof;

FIG. 5 is a bottom view thereof;

FIG. 6 is a front view thereof;

FIG. 7 is a rear view thereof;

FIG. 8 is a first detailed view taken from FIG. 5; and,

FIG. 9 is a second detailed view taken from FIG. 5.

The broken lines illustrate portions of the midsole and outsole for footwear that form no part of the claimed design, as well as environmental structure in the form of a footwear upper that forms no part of the claimed design.
